UNITED STATES PATENT OFFICE.

JAMES PHILLIPS, JR., OF FITCHBURG, MASSACHUSETTS.

DESIGN FOR WOVEN FABRIC.

SPECIFICATION forming part of Design No. 24,747, dated October 8, 1895.

Application filed August 14, 1895. Serial No. 559,288. Term of patent 3½ years.

To all whom it may concern:

Be it known that I, JAMES PHILLIPS, Jr., of Fitchburg, in the county of Worcester and State of Massachusetts, have invented and produced a new and original Design for Woven Fabrics, of which the following is a description.

Reference is to be had to the accompanying drawing, which shows a plan view of a woven fabric embodying my design.

The leading feature of my design consists in a number of independent tuft-like figures raised from the surface of the fabric and arranged in waved lines over the surface of the fabric.

Referring specifically to the drawing, A

designates the body of the fabric, and A' represents the tuft-like figures, each tapering substantially from one end to the other. The tuft-like figures have the appearance of 20 waved lines over the body of the fabric, the tuft-like figures in each line being arranged with the small ends pointed substantially in the same direction on the fabric body.

I claim—

25 The design for a fabric, substantially as herein shown and described.

JAMES PHILLIPS, JR.
